US0D1016364S

(12) **United States Design Patent** (10) Patent No.: **US D1,016,364 S**
(45) Date of Patent: ** Feb. 27, 2024

(54) **LUMINAIRE**

(71) Applicant: **Paro Holding GmbH**, Starnberg (DE)

(72) Inventor: **Axel Meise**, Starnberg (DE)

(73) Assignee: **Paro Holding GmbH**, Starnberg (DE)

(**) Term: **15 Years**

(21) Appl. No.: **35/514,510**

(22) Filed: **Dec. 23, 2021**

(80) **Hague Agreement Data**

Int. Filing Date: **Dec. 23, 2021**

Int. Reg. No.: **DM/220165**

Int. Reg. Date: **Dec. 23, 2021**

Int. Reg. Pub. Date: **Jun. 24, 2022**

(30) **Foreign Application Priority Data**

Jun. 24, 2021 (EM) 008589816-0001
Jun. 24, 2021 (EM) 008589816-0002

(51) **LOC (14) Cl.** **26-05**

(52) **U.S. Cl.**

USPC **D26/88**

(58) **Field of Classification Search**

USPC D26/24, 72, 79, 81, 85, 88, 92, 113, 118

(57) **CLAIM**

The ornamental design for a luminaire, as shown and described.

DESCRIPTION

1. Luminaire
2. Luminaire
- 1.1 : Perspective
- 1.2 : Front
- 1.3 : Back
- 1.4 : Left
- 1.5 : Right
- 1.6 : Bottom
- 1.7 : Top
- 1.8 : Perspective
- 2.1 : Perspective
- 2.2 : Front
- 2.3 : Back
- 2.4 : Left
- 2.5 : Right
- 2.6 : Bottom
- 2.7 : Top
- 2.8 : Perspective

1 Claim, 16 Drawing Sheets
